UNITED STATES PATENT OFFICE.

IVAN EMILE LANHOFFER, OF PARIS, FRANCE.

CEMENT-ROASTING APPARATUS.

Application filed May 24, 1922. Serial No. 563,451.

To all whom it may concern:

Be it known that I, IVAN EMILE LANHOFFER, citizen of the Republic of France, and resident of Paris, in the said Republic, have invented a new and useful Cement-Roasting Apparatus, of which the following is a specification.

This invention relates to a cement roasting apparatus, the said apparatus comprising furnaces or furnace sections of the rotary type.

The principal object of the invention is to provide an apparatus suitable for carrying out a process in which a low temperature treatment of the raw material is immediately followed by a high temperature treatment in a separate furnace, such a process forming the subject of a separate United States patent application Serial No. 563,452, filed May 24, 1922 of even date herewith.

Rotary furnaces heretofore employed for the roasting or calcining of cement have been found to be inefficient as compared with some types of vertical furnace. In spite of all attempts at heat insulation, there has been considerable loss due to radiation owing to the extensive surface areas of these furnaces. Also, in these furnaces, the material is not in such intimate contact with the flame as in the vertical furnaces but may be said to be only indirectly heated as the heating is accomplished partly through the medium of the hot gases and partly through the medium of the heated walls of the furnace.

A further object of the invention is to combine with a sectional rotary furnace fitted with heat control means, a heat recovery apparatus and means for dividing the stream of hot gases issuing from the high temperature treatment so that a desired proportion can be treated for heat recovery and the remainder may be admitted to the low temperature treatment furnace.

Another object is to provide control means for dealing with the gases after heat recovery treatment so that any desired proportion of such treated gases may be admitted to the low temperature treatment.

As will appear, other objects consist in providing means for rendering the heat recovery as efficient and controllable as possible, in providing means for attaining the best possible heat utilization either directly by immediate contact of the gases with the material to be treated or indirectly through the medium of furnace walls and in pro-

viding means for the rapid cooling of the product and the utilization of the heat recovered therefrom in the process of such cooling.

These and other objects will appear from the following description of an apparatus illustrated diagrammatically and by way of example in the annexed drawing, in which:

Figure 1 is a longitudinal section of a two-part furnace fitted with heat recuperating or economizing means, the dotted arrows in this figure indicating the course of the material undergoing treatment, the full line arrows indicating the different courses followed by the gases of combustion, and the broken arrows indicating the course of the recovered gases.

Fig. 2 represents a plan view of the two-part furnace shown in the preceding figure, partly broken away.

Figure 3 is a more or less diagrammatic view of clinker cooling apparatus adapted to be applied to the delivery end of the furnace.

Figure 4 is a cross section on a larger scale of one of the lining elements of the clinker cooler, shown diagrammatically in Figure 3.

Figure 5 is a detail longitudinal section, on a large scale, of a portion of the furnace showing the metallic and refractory linings.

Figure 6 is a detail transverse section of the dust chamber.

Figure 7 is a detail longitudinal section of a modified form of furnace.

Figures 8 and 9 are respectively detail vertical and horizontal sections of the damper, and

Figure 10 is a longitudinal section of the means for cooling the clinkers combined with the furnace.

In Figure 1, *a* is the high temperature furnace or furnace section and *b* is the low temperature furnace or section. The furnace *a* is fitted with a source of heat *a*¹ such as the blow flame burner seen to the left hand of Figure 1 and it is also fitted over its whole length with a strong lining which is insulated as much as possible from the external tube or casing. The function of the furnace *a* is to roast or calcine the material received from the furnace *b*, which material arrives in the furnace *a* in a dried and granulated form at a relatively high temperature and reasonably free from powder.

The raw material is fed into the furnace *b* in a damped form, or, if the wet method is followed, in the form of a paste. In this furnace, the material granulates and is slowly and uniformly dried, and finally is heated to a sufficiently high temperature for delivery to the furnace *a*.

The temperature of the gases escaping from *a* will be usually insufficient for permitting of such gases serving any further useful purpose in that furnace, although that temperature is still too high for reasonable utilization in the furnace *b*. It is therefore proposed to withdraw such gases, or some of them, at this point, and to recover from them the excess of heat which they contain. Owing to their dryness and the small amount of powder borne by them, these gases are in the best possible condition for their treatment in the heat recovery apparatus. This recovery of the excess heat and regulation of the temperature in the low-temperature furnace can be carried out in either one of two different ways. In the first, the gaseous stream is divided and one part is withdrawn and is directed into the apparatus for the extraction of its heat, the remaining part which passes into the furnace *b* being calculated so as to carry sufficient heat for the performance of the operations in the furnace *b*. In the second, the temperature of gases coming from *a* is lowered in the heat recovery apparatus and the gases are then admitted to the furnace *b*.

Thus, the whole of the stream of gases from *a* may be passed through the said apparatus for the extraction of their excess heat and may then be admitted to the furnace *b*, at the lower temperature.

In practice, these two methods will generally be combined because neither the one nor the other alone permits of obtaining the best results in the furnace *b*. It is by the combination of the two methods that it is possible to regulate the temperatures, volumes and quantity of heat of these gases for the purpose of ensuring the greatest economy in their utilization. This is illustrated by Figure 1 in which, at the right hand end of the furnace *a* the escaping gases are divided into two parts, one part passing in a rapid ascending current up the refractory tube *i* and so into the furnace *b*, whilst the other part passes into the chamber *d* and so to the heat recovery apparatus. The first part of these gases is drawn up the tube *i* owing to the suction of the fan at *t* and it is through this tube that the material falls from the delivery end of the furnace *b* into the entry end of the furnace *a*. The dust contained in the substance under treatment and from which it is cleared away by the hot gases themselves by their passage in the tube *i*, is gathered in the chamber *c*, which constitutes the head of the furnace *b* and is disposed in

such a manner that the dust can be deposited there and slid into pits from the bottom of which it can be withdrawn. The second part of the said gases is drawn into the chamber *d* owing to the suction of the fan at *q* and any dust or powder carried by this stream is deposited in the chamber *d* before passing to the heat recovery apparatus at *e*. The latter may be a steam boiler or water heater, and after its passage through *e*, the current may be again divided into two parts the relative values of which may be varied by adjustment of the valves or dampers *f* and *g*. That part which is under control of the valves *f* passes into a chamber *j* and from thence into the furnace *b* where it mixes with the very hot gases coming directly from the furnace *a*. The other part which is under control of the valves or dampers *g* passes through, say, feed water heaters *r* for the boilers at *e* and is delivered by the fan *q* into the factory. The heat still remaining in these gases may be used for the drying of the raw material or of the coal, these gases being suitable for the purpose on account of their small content of oxygen and consequent inability to form an explosive mixture.

The hot gases coming directly from the furnace *a* and passing up the tube *i* enter the surface *b* by way of the annular space around the tube *u* which delivers the colder gases from the heat recovery apparatus. Thus the hot gases in this annular space will heat the material passing through the same which materials are then about to be transferred to the furnace *a*. The tube *u* is in rigid connection with the furnace *b* and revolves with it, the outer end of the tube *u* extending into and giving communication with the chamber *j* into which the gases from the heat recovery apparatus are delivered under control of the valves or dampers *f*.

The valve or damper *h* consists of a block of fire-proof material, which forms one wall of a rectangular funnel into which the substance coming from the preparation furnace *b* falls and by which it is led into the refractory tube *i*, through it falls into the calcination furnace *a*. In the tube *i*, the substance is cleaned of dust by its fall through the current of ascending hot gas coming from the calcination furnace *a*, the volume of which current is regulated by the valve or damper *h*.

By advancing or retarding this valve or damper, the opening of the funnel is decreased or increased which results in an increase or decrease in the volume of the gaseous current.

The lining of the furnace *b* towards its delivery end *b*¹ may be of refractory material carefully insulated from the outer tube or casing whereas that portion *b*² towards the

inlet end for the raw material may have a metallic lining b^2 as the falling temperature at this part permits of this and the metal lining takes up more of the heat of the gases which are about to escape from the furnace b than is taken up by a refractory lining. In fact, the difference in temperature between the lining and the gases is no longer of much importance so that it is 10 of advantage to facilitate by any means the exchange of heat and to remove from the gases before they pass to the chimney the greatest quantity of heat possible.

The general arrangement hereinbefore described permits of easy regulation and control not only of each individual part of the installation but also of the whole plant including the heat recovery apparatus. If the dampers f and g be closed, all the gases 20 from the furnace a will pass into the furnace b and the apparatus will function in a manner similar to an ordinary rotary furnace. In this phase of control it is obviously necessary to moderate the flame so that 25 the disengagement of CO_2 only commences after the entry of the material into the furnace a . The output and heat economy of the furnace are now reduced to that 30 of an ordinary long furnace and the heat recovery apparatus is out of action. If the dampers g and h be fully opened, only a part of the gases from the furnace a is delivered through the tube i into the furnace b and if this part is equal to about $\frac{1}{8}$ to $\frac{1}{10}$ of the whole volume, it may suffice for 35 effecting the drying and heating of the raw material in the dry process in the furnace b . The heat in the remainder of the gases will then be wholly taken up in the heat recovery apparatus. If the working conditions are such as to make this mode of operation preferable, then it would be possible 40 to considerably reduce the dimensions of the chamber j and tube u and even to omit them altogether. Lastly, if the damper f be fully opened and the damper h be almost closed, practically all the gases will pass 45 from the furnace a to the heat recovery apparatus and if the dampers g be closed all these gases will pass from the recovery 50 apparatus to the furnace b . By making the heat recovery apparatus sectional or compartmental, it is easily possible to regulate 55 the amount of heat absorbed therein by opening more or less of the sections or compartments to the passage of the gases, or in other words, varying the heating surface. Generally speaking, this mode of working 60 would suit best the so-called wet process, and if the plant is to be more particularly adapted for working that process it would be possible to pass the gases from the chamber j through the tube u directly into the head c of the furnace b , instead of extending 65 the tube u well into the furnace b . In

such an apparatus, the dimensions of the heaters r and fan q could be greatly reduced.

If there be further added to the regulating means above described, regulating means for varying the intensity of the blow flame and regulating means for varying the speed of rotation of either or both of the furnaces a and b , it will be realized that there are extensive facilities for regulating and controlling the working of the plant for obtaining all kinds of effects. Therefore it is now possible to arrange for the most economical conditions of working for each particular case as it arises.

The course of the material undergoing treatment in the installation is the same in all cases and is as represented in Figure 1, the said material being supplied to the entry end of the furnace b by a suitable feed or distributor, then passing through the furnace b and falling through the tube i into the furnace a and eventually leaving the delivery end of the furnace a in the form of clinker.

The cooler, Figures 3, and 4, is arranged as shown at m^1 , at the delivery end of the furnace a to receive the clinker and cool the same before delivery. It is very advantageous to cool the clinker with great rapidity and to recover from the same as much as possible of the heat. For this purpose, the cooler is adapted for forcing the cooling air to pass through the layer of clinker and owing to its efficient action may be very short in length. The cooler is composed of a number of elements, one of which is seen in detail in Figure 4, bolted in a circular series around the interior of a perforated cylindrical casing or drum. As will be seen, each element comprises a casting l presenting a cavity, the circumferential wall of this casting having a perforation s and the opposite wall being adapted for the fixing therein of a plate m . The elements are mounted in the casing or drum so that the plates m overlap one another but leaves slits or apertures between for the passage of air, and so that the perforations s register with appropriate perforations in the cylinder or drum.

As will be seen from Figure 3, and assuming the cooler to be rotating in the direction of the arrow, the clinker coming from the furnace a is distributed in a layer extending from the lowermost point in the interior for some little distance up the cylindrical interior. The external air enters by the perforations in the casing and through the perforations s into the cavities of the castings l so as to cool the latter over their whole length. The air then passes beneath the plates m and cools the latter and finally passes through the slits or apertures between the plates m and through the layer of clinker

and so into the interior of the casing or drum. A shoulder *n*, Figure 4, at the joint between any plate *m* and its casting *l* prevents the clinker from sliding into the cavity of the casting *l* of an adjoining element, as will be readily understood.

As will be understood from Figure 3, the clinkers will be distributed over only, say, four or five of the elements situated to the right hand of the vertical plane passing through the axis of the drum. Therefore, the air should have access only to those elements which for the time being are carrying clinker and not to the remaining elements. This result is achieved by encircling the drum with a steel belt or band *o* which latter, at the place where the clinker-carrying elements are situated, is diverted from the periphery of the drum by means of pulleys *p*, *p*² and so on. By adjusting the distance apart of the pulleys *p*, *p*² the number of openings *s* uncovered for the admission of cooling air is varied and by displacing the whole pulley arrangement around the periphery of the drum, the air admission zone is correspondingly shifted. It is therefore easy to regulate at will, the admission of cooling air and to force this air to pass through the layer of clinkers. It is to be noted that the furnaces *a* and *b* are shown as having a horizontal disposition in the drawing, but they will be usually inclined for the travel of the material downwards from the entry end to the delivery end. The inclination is usually very slight as, for example, five or six degrees from the horizontal.

From the foregoing, it will be seen that the process is divided into two principal parts namely, the high temperature part taking place in the furnace *a* and the relatively low temperature part taking place in the furnace *b*. However, it is apparent that the part of the process conducted in the furnace *b* may be regarded as itself divided into two parts, the one being conducted in the higher temperature zone of the furnace *b* which is lined with refractory walls and the other in the lower temperature zone of the furnace *b* which is provided with a metal lining for increasing the heat exchange capacity and recovering as much as possible of the heat of the gases prior to their departure from the furnace *b*, as clearly shown in Figure 5. Obviously, therefore, it would be possible to divide the furnace *b* into two parts one having a refractory lining and the other having a metal lining, should that method of working be preferred.

I claim:

1. Apparatus for roasting cement which includes a rotary furnace for low temperature treatment, a rotary furnace for high temperature treatment, a source of heat applied to the latter, feed means located at one

end of the low temperature furnace, and delivery means located at the opposite end of the low temperature furnace; said apparatus comprising, means disposed at the extremity of the entrance of the high temperature furnace for moving the gases of combustion from one furnace to the other in a direction opposite that followed by the substance under treatment, and means for dividing the current of gas issuing from the high temperature furnace whereby only a predetermined amount of the current is admitted to the low temperature furnace.

2. Apparatus for roasting cement which includes a rotary furnace for low temperature treatment, a rotary furnace for high temperature treatment, a source of heat applied to the latter, feed means located at one end of the low temperature furnace, and delivery means located at the opposite end of the low temperature furnace; said apparatus comprising, means disposed at the extremity of the entrance of the high temperature furnace for moving the gases of combustion in said furnaces in an opposite direction to that followed by the substance under treatment in said furnaces, means for dividing the current of gas issuing from the high temperature furnace, whereby only a predetermined amount of the current is admitted to the low temperature furnace directly, means for recovering the heat, and means for passing the remaining gases into the heat recovery means.

3. Apparatus for roasting cement which includes a rotary furnace for low temperature treatment, a rotary furnace for high temperature treatment, a source of heat applied to the latter, feed means located at one end of the low temperature furnace, and delivery means located at the opposite end of the low temperature furnace; said apparatus comprising, means disposed at the extremity of the entrance of the high temperature furnace for moving the gases of combustion in said furnaces in an opposite direction to that followed by the substance under treatment in the furnaces, means for dividing the current of gas issuing from the high temperature furnace whereby only a predetermined amount of current is admitted directly to the low temperature furnace, means for recovering the heat and means for passing the remaining gases into the heat recovery means, a conduit connecting the head of the low temperature furnace to the extremity of the entrance of the high temperature furnace, and valve mechanism for regulating the flow of gases from the high temperature furnace to the low temperature furnace and then into the said heat recovery means.

4. Apparatus for roasting cement which includes a rotary furnace for low temperature treatment, a rotary furnace for high

- temperature treatment, a source of heat applied to the latter, feed means located at one end of the low temperature furnace, and delivery means located at the opposite end of the low temperature furnace; said apparatus comprising, means disposed at the extremity of the entrance of the high temperature furnace for moving the gases of combustion in said furnaces in an opposite direction to that followed by the substance under treatment in the furnaces, means for dividing the current of gas issuing from the high temperature furnace whereby only a predetermined amount of current is admitted directly to the low temperature furnace, means for recovering the heat and means for passing the remaining gases into the heat recovery means, a conduit connecting the head of the low temperature furnace to the extremity of the entrance of the high temperature furnace, valve mechanism for regulating the flow of gases from the high temperature furnace to the low temperature furnace and then into the said heat recovery means, and valve mechanism for regulating the quantity of gas passing from the heat recovery means into the head of the low temperature furnace, said mechanism being mounted over the delivery tubes connecting the heat recovery means and the low temperature furnace.
5. Apparatus for roasting cement which includes a rotary furnace for low temperature treatment, a rotary furnace for high temperature treatment, a source of heat applied to the latter, feed means located at one end of the low temperature furnace, and delivery means located at the opposite end of the low temperature furnace; said apparatus comprising, means disposed at the extremity of the entrance of the high temperature furnace for moving the gases of combustion in said furnaces in an opposite direction to that followed by the substance under treatment in the furnaces, means for dividing the current of gas issuing from the high temperature furnace whereby only a predetermined amount of current is admitted directly to the low temperature furnace, means for recovering the heat and means for passing the remaining gases into the heat recovery means, a conduit connecting the head of the low temperature furnace to the extremity of the entrance of the high temperature furnace, valve mechanism for regulating the flow of gases from the high temperature furnace to the low temperature furnace and then into the said heat recovery means, valve mechanism for regulating the quantity of gas passing from the heat recovery means to the head of the low temperature furnace, said mechanism being mounted above the delivery tubes connecting the heat recovery means and the low temperature furnace, said delivery tubes being centrally disposed at the extremity of the outlet of said furnace which is arranged to leave an annular space sufficient for the delivery of the substance as well as for the flow of that portion of the gas passing directly from the high temperature furnace to the low temperature furnace, and valve mechanism for regulating the proportion of the respective quantities of said directly passing gas and of the gas passing through the heat recovery means, and valve mechanism for regulating the proportions of gas passing from the heat recovery means to the exhaust pipe and to the low temperature furnace respectively.
6. Apparatus for roasting cement which includes a rotary furnace for low temperature treatment, a rotary furnace for high temperature treatment, a source of heat applied to the latter, feed means located at one end of the low temperature furnace, and delivery means located at the opposite end of the low temperature furnace; said apparatus comprising, means disposed at the extremity of the entrance of the high temperature furnace for moving the gases of combustion in said furnaces in an opposite direction to that followed by the substance under treatment in the furnaces, means for dividing the current of gas issuing from the high temperature furnace whereby only a predetermined amount of current is admitted directly to the low temperature furnace, means for recovering the heat and means for passing the remaining gases into the heat recovery means, a conduit connecting the head of the low temperature furnace to the extremity of the entrance of the high temperature furnace, valve mechanism for regulating the flow of gases from the high temperature furnace to the low temperature furnace and then into the said heat recovery means, valve mechanism for regulating the quantity of gas passing from the heat recovery means to the head of the low temperature furnace, said mechanism being mounted above the delivery tubes connecting the heat recovery means and the low temperature furnace, said delivery tubes being centrally disposed at the extremity of the outlet of said furnace which is arranged to leave an annular space sufficient for the delivery of the substance as well as for the flow of that portion of the gas passing directly from the high temperature furnace to the low temperature furnace, and valve mechanism for regulating the proportion of the respective quantities of said directly passing gas and of the gas passing through the heat recovery means, and valve mechanism for regulating the proportions of gas passing from the heat recovery means to the exhaust pipe and to the low temperature furnace respectively.
7. Cement roasting apparatus comprising high and low temperature furnaces connected in series and adapted to be successively

sively traversed in opposite directions by the material to be treated and the gases of combustion, there being a connecting duct between the delivery end of the first furnace and the entering end of the second furnace, a dust deposition chamber arranged at the entering end of the second furnace and adapted to receive a portion of the gases therefrom, a heat exchange apparatus connected with said deposition chamber, means for drawing gases out of the second furnace and through said deposition chamber and said heat exchange apparatus, and means for delivering to the first furnace a pre-determined proportion of the gases cooled in the exchange apparatus, substantially as set forth.

8. Cement roasting apparatus comprising a low temperature treatment furnace, a high temperature treatment furnace, feed means applied to one end of the low temperature furnace, a delivery head and duct applied to the opposite end of the low temperature furnace said duct projecting into the entering end of the high temperature furnace, means for drawing off, cooling and returning to the low temperature furnace a desired proportion of the gases issuing from the high temperature furnace, a metal lining to that end portion of the low temperature furnace which is adjacent to the feed, a refractory lining to the remaining portion of the low temperature furnace, and means for moving gases through said furnaces in opposition to the travel of material through the same, substantially as set forth.

9. In combination, a low temperature rotary cement furnace, feed means at one end and a stationary head at the other end thereof, a high temperature rotary furnace, a connecting duct between said stationary head and the entering end of the high temperature furnace, a source of heat for said high temperature furnace, means for recovering the heat from a portion of the gases issuing from said high temperature furnace and a cooling drum adapted to receive the material delivered from the exit end of the high temperature furnace, said drum comprising on its interior overlapping plates over which the material is distributed in a layer and air admission ports adapted for admitting air to pass between said plates and through the layer of material substantially as set forth.

10. In combination, a low temperature ro-

tary cement furnace, feed means at one end and a stationary head at the other end thereof, a high temperature rotary furnace, a connecting duct between said stationary head and the entering end of the high temperature furnace, a source of heat for said high temperature furnace, means for recovering the heat from a portion of the gases issuing from said high temperature furnace, a cooling drum adapted to receive material delivered from the exit end of the high temperature furnace, said drum comprising on its interior overlapping plates over which the material is distributed in a layer and air admission ports in its peripheral wall for admitting air to pass between said plates and through said layer of material, a travelling band encircling said drum for the greater part of its periphery and an assemblage of band diverting pulleys adapted for diverting said band from a portion of the periphery of said drum substantially as and for the purpose set forth.

11. In combination, a low temperature rotary cement furnace, feed means at one end and a stationary head at the other end thereof, a high temperature rotary cement furnace, a connecting duct between said stationary head and the entering end of the high temperature furnace, a source of heat for said high temperature furnace, means for recovering a portion of the heat issuing from the said high temperature furnace, a cooling drum adapted for receiving material delivered from the exit end of the high temperature furnace said drum comprising on its interior overlapping plates over which the material is distributed in a layer and air admission ports in its peripheral wall for admitting air to pass between said plates and through said layer, a travelling band encircling said drum for the greater portion of its periphery, an assemblage of band diverting pulleys adapted for diverting said band from a portion of the periphery of said drum, and means operative on said assemblage for the bodily adjustment of said assemblage around said drum as well as for the adjustment of the extent of the arc of the drum uncovered owing to the action of the diverting pulleys substantially as and for the purpose set forth.

In testimony, that I claim the foregoing as my invention, I have signed my name this 8th day of May 1922.

IVAN EMILE LANHOFFER,
